UNITED STATES PATENT OFFICE.

RUDOLPH K. TYRA, OF MINNEAPOLIS, MINNESOTA, ASSIGNOR TO F. L. TYRA, OF MINNEAPOLIS, MINNESOTA.

SHINGLE.

Application filed December 4, 1924. Serial No. 753,830.

My invention relates to stamped metal shingles, such as are usually made in imitation of tile, and has for its object to improve the construction thereof in the several particulars hereinafter noted.

Generally stated, the invention consists of the novel construction, arrangement and combinations of parts hereinafter described and defined in the claim.

10 In the accompanying drawings, which illustrate the invention, like characters indicate like parts throughout the several views.

Referring to the drawings:

Fig. 1 is a perspective view showing several of the shingles applied to a roof structure constructed and applied in accordance with my invention;

Fig. 2 is a section on the line 2—2 of Fig. 1;

20 Fig. 3 is an enlarged fragmentary section on the line 3—3 of Fig. 1;

Fig. 4 is a perspective showing in detail one of the anchoring clips;

Fig. 5 is a view corresponding to Fig. 3 but illustrating a slightly modified form of anchoring clip or means; and

Fig. 6 is a perspective showing in detail the anchoring clip shown in Fig. 5.

Fig. 2 shows two shingles applied to a roof, the said roof being indicated by the character A. Each shingle 7 is stamped from sheet metal, has corrugations running from upper to lower extremity, and is formed at its upper edge with an upstanding lap flange 8 and at its lower edge with a downturned lap flange 9, both of said flanges 8 and 9 preferably being formed L-shaped in vertical section. This adapts the two shingles to be overlapped, as shown in Figs. 1, 2 and 3, and to provide for this overlapping, each shingle, just above its lower edge flange 9, has a raised ridge 10 that overlies the upper edge flange 8 of the next lower shingle. Shingles, when thus 45 constructed and overlapped and applied to an inclined roof, will effectually shed water and snow. The flanges 8, in particular, prevent water from backing up under the shingles, even when the shingles are laid on a roof with very slight pitch.

As an important feature, the invention is directed to means for interlocking the lower edge of an upper shingle to the upper edge of an immediately adjacent lower shingle.

55 This means may take different forms, but in

the several forms, the anchoring means will anchor the upper edge of the one shingle to the roof and will serve to anchor the overlapping lower edge of the upper shingle to the roof and to the said lower shingle, without the use of nails exposed to the weather.

60 In Figs. 1 to 4, inclusive, this anchoring means comprises anchoring clips 11 having slightly raised and downwardly projecting anchoring fingers or projections 12. These

65 clips 11 are slightly bowed at their ends so that they closely engage the tops of the corrugations 7' of the shingles and hold the fingers 12 over the underlying corrugation in proper alignment therewith and against lateral shifting movements when a shingle nail

70 13 is passed through a central portion 14 of each clip and through perforations in the corrugations of the shingles, and driven into the underlying roof boards A, as best shown in Fig. 3. It will be noted that the fingers

75 12 have centrally located longitudinal corrugations 12' that diverge upwardly from the immediately underlying corrugation, for a purpose that will presently appear.

80 The shingles will be laid progressively from the lower toward the upper portion of the roof. The first or lower shingle will be first secured to the roof in its upper edge by applying the anchoring clips and nails as just stated, care being taken to drive the nails down against the clips but not far enough to crush the corrugations of the metallic shingles. Each shingle, in its down-

85 turned lower edge flange 9, is formed with 90 perforations 9' through which the fingers 12 of the cooperating anchoring clips may be freely passed. In laying a second shingle, it is first slid upward on the lower shingle in a manner to cause the fingers 12 to pro-

95 ject through the perforations 9', and under this upward action, the oblique corrugation or rib 12' will cam or push the lower portion of said upper shingle tightly against the upper portion of the lower shingle. 100

When the upper shingle has been thus anchored at its lower edge, the clips will be applied to its upper edge, as before described, and of course, the other shingles will be progressively laid in the manner above 105 stated. In this way, the nails 13 are all covered or enclosed and protected from the weather. Moreover, air passages are formed between the roof and the apron portions of the shingles and around the upper portions

110

of the nails. This gives a chance for the circulation of air, which will make the roof cool in the summer and will very greatly reduce rusting of the shingles and rotting of the roof by accumulation of moisture under the shingles. The lower portions of the shingles may be further clamped down and more tightly secured by hammering or pressing down the fingers 12 of the anchoring 5 clips. In this way, the shingles may be so tightly pressed down and anchored that there will be no rattling or vibration thereof under the action of wind. The anchoring clips, except for projecting portions of their fingers, 10 will also be covered and hidden from view.

As is evident, these metal shingles may be made of any suitable material. Usually, however, they will be made of galvanized iron and will be painted either before or 15 after they have been applied to the roof, so that they will give a good imitation of tile.

The construction illustrated in Figs. 5 and 6, so far as the shingles themselves are concerned, is the same or substantially the same as that above described in connection with Figs. 1 to 4, inclusive, but in this construction, the anchoring clips are in the form of metallic fingers 15 that project from and are formed integral with the heads of 20 nails 16. These nails will be driven through suitable perforations in the corrugations of

the shingles and into the roof boards with the fingers 15 properly projecting over the corrugations of the said shingles. Obviously, the fingers 15 will be passed through the 35 passages or slits 9^a of said shingles, and the method of laying the shingles will be the same as already described.

What I claim is:

A shingle in the form of a stamped sheet 40 formed at its upper edge with an upstanding lap flange and at its lower edge with a downturned approximately L-shaped lap flange, said downturned lap flange of the one shingle being arranged to overlap the 45 upstanding upper flange of a lower shingle, the said shingle having a raised ridge extending above its lower lap flange and said shingle having longitudinal corrugations extending from its upper lap flange through 50 the raised ridge and to said lower lap flange, and the upper lap flange of said shingle being also approximately L-shaped, adapting the L-shaped upper and lower flanges of adjacent shingles to be overlapped and 55 nested, said shingle at its lower portion, just above its lap flange, having an opening through which the prong of an anchoring device may be projected as and for the purposes set forth. 60

In testimony whereof I affix my signature.

RUDOLPH K. TYRA.
